PROTECTIVE SLEEVE FOR CHILDREN

Berniece Moller, Piedmont, Calif.

Application May 27, 1935, Serial No. 23,681

2 Claims. (Cl. 128—133)

This invention relates to devices to be worn by children while at play, which will protect their arms against bruises and abrasions should they fall, will prevent them from contacting their faces with their soiled hands, and will also prevent them from placing unclean toys or other objects in their mouths, thus eliminating the possibility of their harming themselves by accidentally scratching their faces or eyes with their finger nails, or by coming in contact with bacteria which are present on the toys or objects with which they are playing.

It is an object of the invention to provide a device of the character described which will not unduly interfere with the freedom of motion of the child's arms.

Another object of the invention is to provide a protective sleeve of the character referred to which is constructed of light-weight materials so as not to impose a burden on the child's arms and, at the same time, which is of sufficient strength to withstand the severe abuses to which a child usually puts a device of this type.

Referring to the drawing:

Figure 1 is a side elevation of the protective sleeve of this invention.

Figure 2 is an end elevation of the device of Figure 1.

Figure 3 is a perspective view of the sleeve showing its application to the person of the wearer and also demonstrating its function in limiting the flexure of the child's arm.

In detail, the device of this invention, as is best shown in Figure 1 of the drawing, comprises a sheet of flexible, preferably transparent material such as celluloid, bent with its opposite ends in overlapping relationship and secured by a plurality of rivets 4, to provide a longitudinally rigid, tubular sleeve 5. All of the rough edges of the sheet, in order to prevent them coming in contact with the wearer's skin and causing cuts or abrasions, are bound with fabric tape 6, which is secured to the sheet by means of stitching 7.

As will be seen, one end of the sleeve is left open and the other end is provided with means for engaging the wearer's arm. This means consists of a pair of diametrically opposed fabric members 8, which are doubled to provide looped casings for engaging an elastic loop wristlet 9, and whose ends are disposed respectively against the inner and outer peripheries of the sleeve and secured by stitching 10 which passes through the sleeve wall and through both ends of each fabric member. The purpose of this construction is to

provide fabric at the bends of the stitches, otherwise, if both ends of the fabric were placed in contact with one surface of the sleeve, the stitching thread where it would be contacting the bare sleeve, would be liable to be cut by the sharp edges of the celluloid about the holes pierced by the needle. The fabric protects the stitches against such cutting.

The purpose of forming the fabric members in separate sections is to provide openings 11 which allow ventilation of the space between the wearer's arm and the sleeve.

Figure 3 shows the sleeve attached to the arm of a wearer. As will be readily seen, the open end of the sleeve, opposite that which carries the attachment means, is passed over the hand and forearm and the wristlet 9 is expanded to pass over the hand and is then allowed to contract to engage the wrist.

It will also be seen that the length of the sleeve is such that, when it is in position, its upper end extends over a portion of the upper arm of the wearer so that his elbow is disposed within the sleeve. When an attempt is made to flex the arm, beyond limits determined by the length of the sleeve, the edge of the sleeve opening encircling the upper arm will be forced against the arm, thus preventing further bending of the arm. The length of the sleeve is such that the wearer may comfortably flex his arm to substantially right angles, but not beyond, since this degree of bend prevents him from reaching his face with his hands or placing the average object held in his hand in his mouth.

The sleeve, besides providing protection for the child in preventing him from accidentally scratching his face or eyes with his finger nails, contacting his face with his soiled hands, or conveying toys or other objects to his mouth, is an excellent guard for his arms and elbows in preventing bruises and abrasions thereof in the event of falls, since, due to the transverse resilience of the sleeve, it will act to absorb some of the shock of the falls. The material of the sleeve being smooth surfaced, and the edges thereof being bound with fabric, no projections or rough portions are present which will cause annoyance to the child while the sleeve is being worn or will cause injury to the child's arm in the event of falls.

The sleeve is of extremely light weight, not being heavier than a few ounces, and therefore will not create an uncomfortable burden for the child.

What is claimed is:

1. A protector sleeve of the character described comprising a sleeve member constructed of flexible material and possessing substantial longitudinal rigidity with transverse resilience, a plurality of loops each secured at one end of said sleeve member in such manner as to extend radially over the adjacent end opening thereof, and a band engageable with the wrist of the wearer, said band being passed through said loops so as to pull the latter tautly across said end opening while the band is engaged with the wearer's wrist, said loops being circumferentially spaced so as to provide ventilation openings into the sleeve member.
2. A protector sleeve of the character described comprising a sleeve member constructed of flex-

ible material and possessing substantial longitudinal rigidity with transverse resilience, a plurality of loop members each formed of a strip of fabric having its ends straddling one end edge of said sleeve member, means for securing said ends to the sleeve member in such manner that the loop members are free to extend radially over the adjacent end opening thereof, and a band engageable with the wrist of the wearer, said band being passed through said loop members so as to tautly pull the latter across said end opening while the wrist band is engaged with the wearer's wrist, said loop members being circumferentially spaced to provide ventilation openings into said sleeve.

BERNIECE MOLLER.
